ELECTRICAL NETWORK

Torbern Laurent, Stockholm, Sweden, assignor
to Telefonaktiebolaget L. M. Ericsson, Stockholm, Sweden, a company of Sweden

Application March 8, 1932, Serial No. 597,599,
and in Sweden March 12, 1931

8 Claims. (Cl. 178—44)

The present invention relates to an electrical network, which is particularly adapted to be inserted in telephone lines or the like for the purpose of equalizing the differences in attenuation or velocity of propagation of the different frequencies in the voice oscillations. Particularly in loaded lines the attenuation is considerably greater for the higher frequencies than for the lower ones, which property of the line constitutes the main cause of the distortion of the voice oscillations. A further cause of distortion, particularly in lines of this kind, consists therein that different frequencies are propagated over the line with different velocities and thus with different phase displacements, the higher frequencies having a smaller velocity of propagation than the lower ones. It is previously known wholly or partly to compensate the said causes of distortion by inserting in the line, for instance on the receiving side, one or more electrical networks the qualities of which in regard to attenuation and velocity of propagation are opposite to those of the line.

The present invention has for its object to bring about a simplified attenuation and phase correcting network of this kind. The network according to the invention consists of an artificial attenuation device or other quadripole inserted in one line branch by means of one input terminal and the corresponding output terminal and preferably composed of series and shunt impedances, further of two inductively coupled coils inserted in the same line branch at opposite sides of the quadripole, and finally of a bridging condenser shunted across the coils and the intervening part of the quadripole, the quadripole being inserted in similar manner in the opposite line branch by means of its remaining input terminal and corresponding output terminal, or, if desired, the said remaining terminals may be directly connected to the corresponding line branch. In the former case the network may consequently be symmetrical in relation to the line branches. The highest frequencies pass directly through the bridging condenser or bridging condensers respectively, which for these frequencies act as short-circuits, whereas the coils act as high resistances. The highest frequencies thus pass the network without being subjected to any further attenuation. For the lowest frequencies, on the other hand, the bridging condensers act as interruptions wherefore said frequencies pass entirely through the quadripole or the artificial attenuation device which should be so selected that its attenuation corresponds to the difference exist-

ing between the attenuation, in the line, of the highest and the lowest frequencies. The intervening frequencies pass partly through the bridging condensers, are partly transmitted inductively between the coupled coils and pass partly through the quadripole or the artificial attenuation device, the frequencies being then subjected to an additional attenuation which is the higher the lower the frequencies are. The result will be that all frequencies are subjected to a total attenuation which is substantially equal to the line attenuation of the highest frequencies.

The invention will be more closely described with reference to the accompanying drawing in which Figure 1 shows diagrammatically an embodiment of an attenuation correcting network according to the invention which network is unsymmetrical in relation to the line, whereas Figure 2 shows a corresponding network which is symmetrical. Figure 3 shows a symmetrical phase correcting network according to the invention. Figure 4 shows a third embodiment. Fig. 5 is a diagram showing the relation between attenuation and frequency in the network according to Figure 2.

The network is provided with one pair of input terminals 1, 2, and one pair of output terminals 3, 4 and is intended to be connected by means of one terminal pair, for instance 1, 2, to an incoming line or line section and by means of the other terminal pair to, for instance, a receiving device. The network is thus inserted by means of the terminals 1 and 3 in one line branch and by means of the terminals 2 and 4 in the other branch. The quadripole or artificial attenuation device A is inserted by means of one input terminal and the corresponding output terminal *a* and *c* respectively in the line branch connected to the network terminals 1, 3. At opposite sides of the quadripole and between the terminals 1 and 3, thus in series with the same line branch, are connected two coils *L*₁, *L*₂ which are inductively coupled together, a bridging condenser *C* being included between those terminals of said coils which are located farthest away from each other. The remaining terminals of the quadripole, thus one input terminal and the corresponding output terminal *b* and *d* respectively, are directly connected to the remaining mutually short-circuited terminals 2, 4 of the network.

It is generally desirable that the network characteristic should be substantially independent of the frequency. The condition for such independence shall in the following be deducted for an attenuation correcting network according to Figure 110

- 1, in which the quadripole A consists of, for instance, an artificial attenuation device composed of series and shunt resistances, it being presumed that the coupling between the coils L_1, L_2 is fixed,
 5 which generally should be the case. The network characteristic, which evidently is alike at both terminal pairs 1, 2 and 3, 4 if the coils L_1, L_2 are alike and the quadripole A is symmetrical with respect to the terminal pairs, may, as is well known, be
 10 expressed through the formula

$$Z = \sqrt{Z_k \cdot Z_t}$$

15 in which Z_k and Z_t denote the short-circuit characteristic and the no-load characteristic respectively which may be calculated in a simple manner. For this purpose, it is assumed that on each terminal pair 1, 2 and 3, 4 respectively in Figure 1 is impressed a voltage V_1 and V_2 respectively
 20 which at each side is reckoned positive in an upward direction. The current distribution in the network caused hereby may be assumed to have arisen through superposition of two voltage and current conditions. If thus the input and output currents are denoted I_1 and I_2 we have the following expressions
 25

$$V_2 = V_0 + v \quad I_2 = \frac{1}{2}I_0 + i$$

$$V_1 = V_0 - v \quad I_1 = -\frac{1}{2}I_0 + i$$

30 In the expressions for I_1 and I_2 the terms $\frac{1}{2}I_0$ and $-\frac{1}{2}I_0$ represent the current condition which would take place if V_2 and V_1 had both the same value V_0 and the same direction, while the currents i represent the current condition which would take place if V_2 and V_1 had the same value v and opposite directions.

35 If $L_1 = L_2 = L$ and if R_1 denotes the impedance between short-circuited terminals a, c on the one hand and short-circuited terminals b, d on the other hand and if, finally, R_2 denotes the impedance between the terminals $a-c$ we have for one of the superposed conditions in which the voltage V_0 is impressed upon the impedance R_1 and $j\omega L$ in series.
 40

$$V_0 = I_0(j\omega L + R_1) \quad 1.$$

45 and for the other condition in which the voltage v is impressed upon the impedances R_2 and

$$50 \quad \frac{1}{j\omega C}$$

in parallel.

$$2v = i \cdot \frac{R_2}{1 + j\omega C \cdot R_2} \quad 2.$$

55 If the terminals 1, 2 are short-circuited we have

$$V_1 = V_0 - v = 0$$

$$V_2 = 2V_0 = 2I_0(j\omega L + R_1)$$

$$60 \quad I_2 = \frac{1}{2}I_0 + 2I_0 \cdot \frac{(j\omega L + R_1) \cdot (1 + j\omega C \cdot R_2)}{R_2}$$

thus

$$65 \quad Z_k = \frac{V_2}{I_2} = \frac{4R_2(j\omega L + R_1)}{R_2 + 4(j\omega L + R_1) \cdot (1 + j\omega C \cdot R_2)} \quad 3.$$

If the terminals 1, 2 are open we have

$$70 \quad I_1 = -\frac{1}{2}I_0 + i = 0$$

$$I_2 = \frac{1}{2}I_0 + i = I_0$$

$$75 \quad V_2 = I_0 \left[(j\omega L + R_1) + \frac{1}{4} \cdot \frac{R_2}{1 + j\omega C \cdot R_2} \right]$$

thus

$$75 \quad Z_t = \frac{V_2}{I_2} = \frac{R_2 + 4(j\omega L + R_1) \cdot (1 + j\omega C \cdot R_2)}{4(1 + j\omega C \cdot R_2)} \quad 4.$$

From 3 and 4 we obtain

$$Z = \sqrt{Z_k \cdot Z_t} = \sqrt{\frac{1 + j\omega L}{R_1 \cdot R_2} \cdot \frac{1 + j\omega C \cdot R_2}{1 + j\omega C \cdot R_2}} \quad 80$$

The condition in order that Z shall be independent of the frequency is that

$$\frac{L}{C} = R_1 \cdot R_2$$

thus

$$Z = \sqrt{R_1 \cdot R_2} = \sqrt{\frac{L}{C}}$$

For very high frequencies which do not pass through the quadripole the network characteristic is determined solely by the quantities L and C . For the lowest frequencies on the other hand which pass completely through the quadripole the network characteristic is determined by the impedances R_1 and R_2 of the quadripole. Under all 90 conditions the network characteristic will, however, according to the above be the same.
 95

Figure 2 shows a symmetrical embodiment of the network according to the invention and differs from Figure 1 thereby that the terminals b, d , instead of being directly connected, in a short-circuited condition, to the line branch connected to the network terminals 2-4, are inserted in said branch in the same manner as the terminals a, c are inserted in the opposite branch. Outside the terminals b, d and in series with the line branch are thus inserted two coils L_3, L_4 which are inductively coupled together, and between those of the terminals of said coils which are located farthest away from each other is connected a bridging condenser C . All four coils L_1 to L_4 are preferably wound on a common iron core and thus form together a transformer provided with a middle tapping both at the primary and at the secondary side, to which terminals the 100 quadripole is connected. In this case the quadripole consists of an artificial attenuation device composed of series and shunt resistances the attenuation value of which device may be adjusted by means of a suitable control member. The 105 bringing together of all ohmic resistances of the network in a single adjustable artificial attenuation device renders possible a very convenient adjustment of the network for different requirements of additional attenuation. Preferably the 110 condensers C are mutually alike and the coils L_1 to L_4 115 mutually alike.
 120

Figure 3 also shows a symmetrical network which differs from the network according to Figure 2 only therein that the quadripole does not consist of an artificial attenuation device but of an artificial line KL acting as a delaying arrangement and composed of series inductances and shunt condensers. This network is intended to be used for effecting phase correction in a loaded 125 line or the like. The lowest frequencies pass wholly through the artificial line KL and are there subjected to a phase distortion corresponding to the differences between the phase distortion of the highest and the lowest frequencies in 130 the line, whereas the highest frequencies pass directly through the bridging condensers C , and the intermediate frequencies pass partly through said condensers and partly through the artificial line 135 and are subjected to a phase lag which is the greater the lower the frequencies are.
 140

Under certain contingencies the quadripole, 145 may consist of a combination of an artificial damping device KD and an attenuation less artificial line KL as illustrated in Figure 4.
 150

In Figure 4 are shown some attenuation curves for a network according to Figure 2. The attenuation b of the network is plotted as a function of the frequency at different values of the artificial attenuation.

- Curve I corresponds to 0.25 Neper in the artificial attenuation
 Curve II corresponds to 0.20 Neper in the artificial attenuation
 Curve III corresponds to 0.15 Neper in the artificial attenuation
 10 Curve IV corresponds to 0.10 Neper in the artificial attenuation

It is also conceivable that the quadripole may consist of a so called negative attenuation, i. e. an amplifier. Such an arrangement may be suitable for instance if it is desired to send high frequency signals over a telephone line provided with amplifiers without said signals disturbing the low frequent telephone conversations or otherwise influencing the amplifiers. Each amplifier is then arranged similarly to the quadripole A in a network according to the invention. At a suitable dimensioning of the network the low frequencies within the voice frequency range will pass through the amplifiers in the usual manner whereas the high frequencies above the voice frequency range will pass by the amplifiers.

I claim:—

1. An electrical network particularly for the elimination of linear distortion in telephone lines, comprising a quadripole network having a certain attenuation and being inserted in one line branch by means of one input terminal and the corresponding output terminal) a and c respectively, two coils (L_1, L_2) inserted in the same line branch at opposite sides of the quadripole and coupled together inductively, and a bridging condenser (C) shunted across the coils and the intermediate part of the quadripole, the remaining terminals (b, d) of the quadripole being connected to the opposite line branch.
- 40 2. An electrical network as claimed in claim 1,

characterized in that the terminals (b, d) of the quadripole are mutually short-circuited and directly connected to the corresponding line branch.

3. An electrical network particularly for elimination of linear distortion in telephone lines, comprising a quadripole network having a certain attenuation, said network being inserted in one line branch by means of one input terminal and the corresponding output terminal and in the other line branch by means of its two other terminals, a pair of coils in each line branch, the coils of each pair being inserted at opposite sides of the quadripole and coupled together inductively, and one bridging condenser shunted across each pair of coils and the intermediate part of the quadripole.

4. An electrical network as claimed in claim 3, characterized in that the pairs of coils (L_1, L_2) and (L_3, L_4) respectively, which are inserted each in one line branch, are wound on a common iron core.

5. An electrical network as claimed in claim 1, characterized in that the quadripole consists of an artificial attenuation device (KD) composed of series resistances and shunt resistances and preferably adapted to be adjusted, for instance by varying the number of links.

6. An electrical network as claimed in claim 1, characterized in that the quadripole consists of an artificial line (KL) preferably composed of series inductances and shunt condensers.

7. An electrical network as claimed in claim 1, characterized in that the quadripole consists of a combination of an artificial attenuation device and an attenuation-less artificial line.

8. An electrical network as claimed in claim 1, characterized in that the quadripole has a negative attenuation.
